UNIVERSAL ENGINE REPAIR FIXTURE
 Warren R. Seibert, 24533 Ross Ave., Dearborn, Mich.
 Filed Dec. 18, 1961, Ser. No. 159,830
 8 Claims. (Cl. 269—71)

This invention relates to engine repair fixtures and, in particular, to universal engine repair fixtures enabling the engine under repair to be swung into different positions for most efficient working operation.

One object of this invention is to provide an engine repair fixture which is adapted to hold a small engine in any one of a number of positions of adjustment or, in the alternative, to hold any one of a number of different makes or models of engines so as to enable the repair man to select the position most conducive to facilitating his repair work.

Another object is to provide an engine repair fixture of the foregoing character which is adapted to be mounted on and secured to a work bench or other suitable supporting structure and tiltable relatively thereto for convenient positioning of the engine.

Another object is to provide an engine repair fixture which is convertible to the reception either of horizontal engines having vertical crankshafts or of vertical engines having horizontal crankshafts.

Another object is to provide an engine repair fixture of the foregoing character which holds the engine rigidly in either an upright or tilted position and locks it firmly in that position, thereby leaving the repair man with both of his hands free for performing his repair or maintenance work and not requiring him to employ either of his hands for assisting in holding the engine.

Other objects and advantages of the invention will become apparent during the course of the following description of the accompanying drawing, wherein:

FIGURE 1 is a top plan view of an engine repair fixture according to one form of the invention as mounted upon the top of a workbench;

FIGURE 2 is a front elevation of the engine repair fixture shown in FIGURE 1;

FIGURE 3 is a side elevation of the engine repair fixture shown in FIGURES 1 and 2, with two different tilted positions of adjustment around a horizontal axis, shown in dotted lines;

FIGURE 4 is an enlarged fragmentary horizontal section taken along the line 4—4 in FIGURE 2, showing details of the fixture tilting locking arrangement;

FIGURE 5 is a vertical section of the structure of FIGURE 4, taken along the line 5—5 in FIGURE 2;

FIGURE 6 is an enlarged fragmentary horizontal section taken along the line 6—6 in FIGURE 3, showing the arrangement for locking the engine holder after adjustment around a vertical axis of rotation; and

FIGURE 7 is a rear elevation of a modified engine holder for vertical engines interchangeable with the engine holder shown in FIGURES 1, 2 and 3.

Hitherto small engines while being repaired have been ordinarily placed on a work bench and held down with one hand of the workman while he used the other hand for holding tools in order to make repairs or adjustments. Such a requirement left the workman only one hand for effective use and handicapped a short workman, particularly as regards carrying out repair operations on the top or upper part of the engine. Again, the procedure of holding the engine while working upon it varied with the type of engine, whether a horizontal engine having a vertical crankshaft or a vertical engine having a horizontal crankshaft.

The present invention eliminates these disadvantages

by providing a universal engine repair fixture having the advantages set forth in the foregoing objects.

Referring to the drawing in detail, FIGURES 1 to 3 inclusive show a universal engine repair fixture, generally designated 10, according to one form of the invention as consisting generally of an adjustable base structure 12 and an engine holder 14 especially adapted for holding horizontal engines with vertical crankshafts. The base structure 12 includes a base bracket 15 with a base plate 16 preferably of elongated shape having holes 18 therein for receiving bolts, screws or other fasteners 20 by which the base structure 12 is secured to the top 22 of a work bench 24 or other supporting structure. Secured as by welding to the base plate 16 in spaced parallel relationship are vertical side plates 26 and 28 (FIGURE 2) drilled horizontally in alignment to receive a horizontal axle or shaft 30 secured in position by a set screw or other locking device 32.

Pivottally mounted upon the axle 30 is a swinging or tilting support 33 having a base block 34 drilled horizontally for receiving the axle or shaft 30. Secured to the top of the block 34 as by welding is an upstanding tubular member 36 having a normally vertical bore 38 therein (FIGURE 4). Also secured as by welding to one side 20 of the block 34 and tubular member 36 is a quadrant plate 40 (FIGURE 5) which is likewise drilled for the passage of the axle or shaft 30 and which is provided with a plurality of holes 42 at the same radius from the center of the axle 30. Secured as by welding to one 25 side plate 26 is a tubular barrel 44 coaxial with any selected one of the holes 42 and containing a locking bolt 46 reciprocable within the barrel 44 and having a locking pin 48 provided with a knurled head 50 adapted to be grasped by the operator.

The locking pin 48 is of such a diameter as to loosely and reciprocably pass through a hole 52 in the side plate 26 coaxial with the barrel 44 and is provided with a stop collar or enlargement 54 intermediate its opposite ends (FIGURE 4). The stop collar 54 is normally urged 30 into engagement with the side plate 26 by a helical compression spring 56, the opposite or outer end of which engages an annular spring abutment 58 welded or otherwise secured within the outer end of the tubular barrel 44.

Slidably and rotatably received within the bore 38 of 45 the upstanding tubular member 36 of the base structure 12 is a stem or shaft 60 of the engine holder 14. The shaft 60 is preferably welded at its upper end to the under side of the rearward portion of an open-centered engine mounting plate or platform 62 having an opening 64 in the central portion thereof leaving an approximately rectangular peripheral portion 66 having an upstanding back or edge plate 68 welded in part to the horizontal engine mounting plate 62 and in part to the vertical stem 60. The vertical back plate 68 extends 50 below the level of the mounting plate 62 and is connected at its opposite ends to the opposite sides of the engine mounting plate 62 by triangular gusset plates or braces 70 welded or otherwise secured thereto. Secured as by welding to the upper central portion of the back plate 68 is a horizontal shaft or stem 72 corresponding in diameter 55 to the vertical shaft or stem 60 and interchangeable with it in the bore 38 of the tubular member 36 of the base structure 12.

The tubular member 36 of the base structure 12 is provided 60 on its rearward side with a boss 74 (FIGURE 6) which is drilled and threaded horizontally as at 76 to receive a locking thumb screw 78 having a knurled head 80 (FIGURE 6). The tip of the screw 78 enters an annular groove or keyway 81 in the stem or shaft 60. Secured as by welding to the peripheral part 66 of the engine mounting plate 62 at circumferentially-spaced loca- 65

tions are two upstanding locating pins 82, and formed in the same part 66 near the four corners thereof are four circumferentially-spaced holes 84, three of which are occupied by three rotary engine holddown or clamping devices, generally designated 86. The fourth and unoccupied hole 84 is adapted to receive one of the clamping devices 86 which is transferred to it from one of the other holes 84 in order to accommodate certain makes or models of engines requiring different positions thereof. Each of the holddown devices 86 consists of an internally-threaded-knurled knob 88 mounted beneath the mounting plate 62 and threadedly receiving the shank of a screw 90 carrying beneath its upper end 92 an angle arm 94 (FIGURE 2), the peripheral portion 66 being drilled for the passage of the pin 90. Arranged between the mounting plate 62 and the angle arm 94 is a helical compression spring 96 which urges the knob 88 upward against the lower side of the engine mounting plate 62. The construction of each holddown device 86 is such that the angle arm 94 may be swung or rotated around the vertical axis of its respective pin 90 into a position most convenient for engaging the engine base or crankcase rim (not shown).

The modified engine holder, generally designated 100, shown in FIGURE 7 is adapted to be interchangeable with the engine holder 14 within the base structure 12 for holding vertical engines with horizontal crankshafts. The engine holder 100 includes an approximately rectangular mounting plate 102 equipped with elongated corner and intermediate slots 104 and 106 for receiving engine hold-down bolts or other fasteners or clamps (not shown). Welded or otherwise secured to the central portion of the mounting plate 102 is a base plate 108 to which is welded or otherwise secured a stem or shaft 110. The latter is of substantially the same diameter as the stem or shaft 60 of the engine holder 14 so as to be interchangeable within the bore 38 of the tubular member 36 of the base structure 12.

In the operation of the engine holding fixture 10, let it be assumed that a horizontal engine with a vertical crankshaft is to be worked upon and that the pan thereof has been removed so as to expose the crankshaft. The engine is then placed upon the mounting plate 62 of the engine holder 14 in such a manner that the flanged edge portion of the crankcase fits under the angle arms 94, which have been moved to their raised positions by rotating the threaded knobs 88 to permit upward motion of the screws 90. Certain makes or models of engines are provided with recesses suitably located for receiving the locating pins 82, whereas other engines have a projection or pin adapted to enter the hole 84. The operator then rotates each of the knobs 88 so as to pull each screw 90 downward so as to bring each angle arm 94 tightly into clamping engagement with the engine crankcase rim.

The operator now adjusts the fixture 10 to locate the engine in the most convenient position for the particular repair or maintenance operations which he is to perform. To do this, he may loosen the locking thumb screw 80 so as to permit rotating the engine holder 14 around the axis of the stem 60, tightening the screw 80 to clamp the holder 14 in its horizontally-adjusted position. If it is more convenient for him to work upon the engine in a position of the fixture 10 other than the vertical position thereof shown in FIGURES 1 and 2, and in solid lines in FIGURE 3, the workman holds the engine and its attached mounting holder 14 with one hand while he pulls outward upon the knurled head 50 of the locking pin 48 with the other hand so as to remove the locking pin 48 from locking engagement with the vertical position hole 42, holding the head 50 in its outer position while he swings the tubular member 36 into an inclined position shown in the upper dotted lines of FIGURE 3, or into the horizontal position shown in the lower dotted lines thereof. He then releases the head 50 of the locking bolt 46,

the pin 48 of which proceeds to enter the newly selected hole 42 in the adjusted position of the engine holder 14. By this procedure, the engine (not shown) is firmly and rigidly held in its most efficient position of repair or maintenance, whereupon the workman proceeds with his repair or maintenance work in the usual manner.

In the event, however, that repairs on a particular make or model of engine are of such character that the mounting plate 62 of the engine holder 14 is most conveniently used in an upstanding position, the operator places the stem 72 in the bore 38 of the tubular member 36 of the base structure 12 rather than the stem 60 and locks it in position by the locking screw 80. The remaining operations remain otherwise the same.

To repair a vertical engine with a horizontal crankshaft, after removing the pan thereof from the crankcase, the operator removes the engine holder 14 from the base structure 12 and substitutes for it the modified engine holder 100, inserting the shaft or stem 110 in the bore 38 of the tubular member 36 of the base structure 12 in place of the stem 60 or 72 of the engine holder 14. He locks the modified engine holder 100 in position by means of the locking screw 80 and then bolts the crankcase of the engine to the mounting plate 102 by means of bolts or other fasteners inserted through the elongated slots 104 or 106, or both, as the circumstances dictate. He then proceeds to adjust the modified engine holder 100 and the engine thereon to the most convenient working position by the use of the locking bolt 46 and quadrant plate 40 in the manner described above.

What I claim is:

1. A universal engine repair fixture, comprising a base structure having a base plate adapted to be secured to a work bench or the like,

said plate having a device thereon with a pivot axis disposed substantially parallel thereto and a swinging support having one end thereof pivotally mounted on said pivot device for swinging motion between positions substantially perpendicular and substantially parallel to said base plate; and an engine holder having an engine mounting platform with an engine-holding peripheral portion surrounding an enlarged central engine access opening, a first means connecting said engine mounting platform to said swinging support at a location remote from said pivot device, and engine hold-down elements mounted on said platform in peripherally-spaced relationship therewith.

2. A universal engine repair fixture, according to claim 1, wherein said connecting means includes a supporting member detachably connected to said swinging support.

3. A universal engine repair fixture, according to claim 2, wherein said supporting member is rotatably mounted in said swinging support.

4. A universal engine repair fixture, according to claim 3, wherein releasable clamping means is disposed between said supporting member and swinging support in releasable clamping relationship therewith.

5. A universal engine repair fixture, according to claim 2, wherein said swinging support has a bore therein with its axis disposed substantially perpendicular to said pivot axis, and

65 wherein said supporting member is rotatably mounted in said bore.

6. A universal engine repair fixture, according to claim 5, wherein a threaded clamping fastener is threaded through said swinging support into said bore and into clamping engagement with said supporting member.

7. A universal engine repair fixture, according to claim 1, wherein said swinging support includes a plurality of locking holes disposed in an arcuate path centered upon the axis of said pivot means, and

wherein said base structure carries a locking device selectively engageable with one of said holes in each of a plurality of different positions of tilt of said swinging support.

8. A universal engine repair fixture, according to claim 7, wherein said swinging support includes a locking plate containing said locking holes, and

wherein said base structure includes a side plate disposed adjacent said locking plate and a locking member movably mounted on said side plate for motion into and out of locking engagement with a selected one of said locking holes corresponding to a selected position of tilt of said swinging support.
